UNITED STATES PATENT OFFICE.

GEORGE W. BLAKE, OF WYANDOTTE, MICHIGAN, ASSIGNOR TO THE GEO. W. BLAKE MFG. COMPANY, OF WYANDOTTE, MICHIGAN, A CORPORATION OF MICHIGAN.

RECEPTACLE-FILLING MACHINE.

Application filed June 4, 1920. Serial No. 386,529.

To all whom it may concern:

Be it known that I, GEORGE W. BLAKE, a citizen of the United States of America, residing at Wyandotte, in the county of Wayne and State of Michigan, have invented certain new and useful Improvements in Receptacle-Filling Machines, of which the following is a specification, reference being had therein to the accompanying drawings.

In my Patent No. 1,278,097 granted Sept. 10, 1918, there is disclosed a can filling machine that may be used for filling cans, cartons, containers or receptacles with granular, pulverized or loose matter, for instance, sugar, salt, etc., and the machine may also handle liquid, as molasses and any free flowing fluid. The machine includes a main frame, power and driven shafts; main and auxiliary feed reservoirs with automatic controlling devices between the reservoirs; electrically operated feed shut off devices for the auxiliary reservoirs; pneumatic vibrators for the auxiliary reservoir and a valve controlling the operation of the vibrators; rotary carrier and scale platforms; power distributor for the electrical devices; and automatic loading and unloading devices for the rotary carrier. In constructing the machine, it was found that certain improvements could be made which would not only simplify the construction, but insure a more perfect operation and control especially when handling certain kinds of material.

Starting in at the top of the machine the first improvement is an automatic feed controlling device for the auxiliary reservoir, and within the reservoir or the discharge spouts thereof are agitators which prevent the material from the auxiliary reservoir clogging the spouts and the discharge nozzles thereof.

The next improvement is in connection with the electrically operated shut-off devices for the auxiliary reservoir and by a novel arrangement of toggle levers a better action is obtained irrespective of the nature of the material to be controlled by the shut-off devices.

Further down in the machine is the rotary carrier and its scale platforms and it is here that numerous improvements were made, some of which are in the form of safeguards

and others to provide a more reliable automatic loading and unloading of cans or similar receptacles. 55

All of the improvements and changes which I have made in connection with the machine disclosed in my prior patent will be hereinafter described and then claimed, 60 and reference will now be had to the drawings, wherein—

Figure 1 is a vertical sectional view of the machine, partly in elevation and partly broken away; 65

Fig. 2 is a horizontal sectional view of the same taken on the line II—II of Fig. 1;

Fig. 3 is a plan of the machine showing the automatic feed control device for the auxiliary reservoir; 70

Fig. 4 is a plan of a portion of the auxiliary reservoir showing a modified form of agitator;

Fig. 5 is a side elevation of the same;

Fig. 6 is a side elevation of a portion 75 of the rotary carrier and a scale platform thereof;

Fig. 7 is an elevation of one of the electrically operated feed shut off devices for the auxiliary reservoir, partly broken away 80 and partly in section;

Fig. 8 is a longitudinal sectional view taken on the line VIII—VIII of Fig. 7;

Fig. 9 is a horizontal sectional view taken on the line IX—IX of Fig. 8; 85

Fig. 10 is a cross sectional view taken on the line X—X of Fig. 2, and

Fig. 11 is an enlarged detail sectional view of an adjustable trip member.

As in my former machine, there is a base 90 or foundation 1 provided with a plurality of uprights and some of these uprights have been designated 2, 3 and 4 with the upper ends thereof connected by a three-arm spider 5. The uprights are otherwise connected as 95 will hereinafter appear, particularly by a three-arm spider 6 adjacent the base 1 of the machine, and this spider cooperates with the spider 5 in providing bearings or journals for a vertically disposed drive shaft 7 100 which may be operated from an electric motor or suitable source of power.

Suitably connected to the spider 5 is a circular cover plate 8 for an annular auxiliary reservoir composed of an inner wall 9 and an outer wall 10, said walls being 105

mounted on a bottom plate 11 fixed to the vertical shaft 7, as at 12, so as to rotate therewith. The annular walls 9 and 10 co-operate in providing an annular compartment which may be filled from a filling connection 13 carried by the cover plate 8, and extending into the filling connection 13 is the flexible discharge tube or filling spout 14 of a main reservoir (not shown). The flexible discharge tube 14 may be in the form of a piece of hose bearing against a bracket 15 supported above the cover plate 8 and pivotally connected to the bracket 15 is a yoke 16 having a presser member 17 adapted to engage the discharge tube 14 and collapse said tube towards the bracket 15, as shown by dot and dash lines in Fig. 1. The discharge tube 14 has been shown as partially closed in Fig. 3 and to accomplish a shut off of the tube passage the yoke 16 has a side arm 18 pivotally connected by a link 19 to a lever 20 fulcrumed on an upright 21, carried by the cover plate 8. The lever 20 extends transversely of the cover plate to a point diametrically opposite from the discharge tube 14 where the end of the lever is loosely connected, as at 22, to a rod 23 extending through a guide 24 of the cover plate 8 into the annular compartment of the auxiliary reservoir. The inner end of the rod 23 has a shoe 25 adapted to bear on the material within the auxiliary reservoir, said shoe being somewhat segment shaped with one end thereof inclined so that it will easily ride over the surface of the material in the reservoir as said reservoir fills.

The elements 15 to 25 inclusive constitute automatically actuated means for regulating the supply of material to the auxiliary reservoir, and such means permit of the supply being controlled irrespective of the kind of material supplied to the reservoir.

Suitably connected to the bottom plate 12 are a plurality of circumferentially disposed and equally spaced discharge nipples 26 and attached to each nipple is a flexible tubular discharge spout 27, preferably made of a piece of hose having walls that may be easily collapsed and pressed towards each other. The discharge spout 27 extends into openings 28 of a circular plate 29 secured to the shaft 7 and this circular plate may be provided with a nozzle for the discharge spout so that various sizes and kinds of receptacles may be readily filled.

Suspended in each discharge nipple is an agitator 30 to prevent material or matter unduly caking, packing down, or solidifying within the nipple and the bottom of the auxiliary reservoir. The agitators 30 may be in the form of a flat piece of material provided with a scalloped or sinuous member projecting from the sides thereof and the agitators are loosely connected to cranks 31 of crank shafts 32 which extend through

the outer wall 10 of the auxiliary reservoir and are journaled in bearings 33 on the bottom plate 11.

The crank shafts 32 are provided with rolls 34 that ride against a track 35 supported by brackets 36 from the uprights 2, 3 and 4 of the machine. The track 35 is stationary and segment shaped in plan, as shown in Fig. 3, and as the rolls 34 contact therewith the shafts 32 are revolved to impart a somewhat reciprocable movement to the agitators 30 within the discharge nipples 26. Associated with each discharge nipple and spout is an electrically operated feed shut off device, best shown in Figs. 1, 7, 8 and 9, and each device comprises a solenoid bracket 37 depending from the bottom plate 11 of the auxiliary reservoir. The bracket 37 supports a set of solenoids 38 having the cores 39 thereof connected by a cross head 40, and attached to said cross head and extending through the bracket 37 is a plunger 41 which is encircled by a coiled expansion spring 42, the purpose of which will herein-after appear.

Suitably attached to the sides of the bracket 37 are brackets 43 having confronting channel guides 44 at the lower edges thereof and slideable in said channel guides are the ends of opposed shut off members 45 and the ends of rods 46 located adjacent said shut off members. The shut off members 45 are at opposite sides of the spout 27 and said shut off members have presser blocks 47, preferably made of rubber, adapted to collapse the walls of the spout and close the same as shown at the left hand side of Fig. 1. The shut off members 45 are connected by links 48 to the rods 46 and the shut off members have depressed portions 49 providing clearance for the links 48 and also toggle members 50 which are pivotally connected, as at 51, to the ends of a fork 52 pivotally connected to the lower end of the plunger 41, said fork being fulcrumed on a transverse bearing pin 53 connecting the brackets 43.

The arrangement of the links 48 is such that when the pivotal connections 51 of the toggle members 50 are raised and lowered the rods 46 will be shifted to move the shut off members 45 to and from each other. For instance, the expansive force of the spring 42 holds the plunger 41 normally elevated with the rods 46 separated and the shut off members 45 closed for pressing against the wall of the spouts 27 to hold them collapsed and closed. When the solenoids 38 are energized the plunger 41 is lowered and the rods 46 are shifted towards each other causing the shut off members 45 to open or separate thereby permitting the contents of the auxiliary reservoir to flow through the spout 27. The shut off device has been shown in Figs. 7 to 9 inclusive as though the solenoids 38 were

energized, and it will be noted that when the solenoids are de-energized that the expansive force of the spring 42 immediately closes the shut off members 45. This is a safeguard in case anything should happen to interfere with the electrical connections of the solenoids 38, otherwise the shut off members 45 might be open and the material flow from the spout 27.

10 Mounted on the shaft 7, below the circular plate 29 is a rotary carrier 54 which has its peripheral edges cut away to provide clearance for a plurality of scale platforms 55 corresponding in number to the discharge 15 spouts 27. Each scale platform has a depending stirrup 56 pivotally connected, as at 57, to a yoke 58 on the outer end of a scale beam 59. The yoke 58 of the scale beam is pivotally connected, as at 60, to a stirrup 20 shaped hanger 61 of the carrier 54 and this hanger is connected by links 62 to the yoke 56. The constructive arrangement of the 25 scale beam 55 is such that it is normally maintained in the same horizontal plane as the peripheral edges of the rotary carrier 54, and with the scale platform of the beam and poise type it is possible to set the poise of the scale so that the platform will not be overbalanced until a prescribed quantity of 30 material has entered a can or receptacle on the platform.

Above each platform 55 is a receptacle receiving U-shaped member 63 supported by a turn post 64 and constantly maintained in engagement with a stop pin 65 by a coiled 35 spring 66 on the post 64. The expansive force of the spring 66 holds the receptacle receiving member 63 against the stop pin 65 but permits of the receptacle receiving member 40 yielding as it receives a receptacle. The post 64 extends upwardly through a receptacle abutment 67 and it is to this abutment that one of the convolutions of the spring 66 may be connected while the other convolution 45 of the spring is fastened to the post 64 or the receptacle receiving member 63.

On the scale platform 55, adjacent the inner edge thereof, are insulated binding 50 posts 68 and 69, the former supporting a silent switch arm 70 adapted to contact with a contact member 71 of the binding post 69. Intermediate the ends of the switch arm 70 is an insulated projection 72, and this projection 55 protrudes below the can receiving member 63 so that a can or receptacle placed on the scale platform 55 will engage the projection 72 and shift the switch arm 70 until it engages the contact member 71 and establishes an electrical connection between the 60 binding posts 68 and 69.

The scale platform 55 has a depending bracket 73 and the rotary carrier 54 has a similar depending bracket 74. The brackets 73 and 74 are loosely connected together by a 65 switch beam 75 having a contact member or

blade 76 intermediate the ends thereof adapted to enter a knife switch 77 supported by an insulator 78 depending from the rotary carrier 54. So far it is apparent that when a receptacle is placed on the platform 55 the 70 switch arm 70 is closed, and as the receptacle is filled and the platform 55 lowered, the switch beam 75 is actuated to move the contact member or knife 76 out of engagement with the knife switch 77 and thereby break 75 an electric circuit which will now be considered in connection with the electrical equipment of the machine.

Suitably fixed on the three arm spider 6 is a brush holder 79 having brushes 80 and 81 in circuit with a suitable source of electrical energy, (not shown). The brushes 80 and 81 contact with distributor rings 82 and 83 respectively carried by an insulator 84 mounted on the vertical drive shaft 7, and the distributor ring 82 is connected by insulated electrical conductors 84 to the binding post 69 of the platform switches. The binding posts 68 of said platform switches are connected by conductors 85 to the carrier knife 90 switches 77 and these carrier knife switches have conductors 86 extending through insulators 87 on the drive shaft 7 and upwardly to another insulator 88 mounted on the drive shaft 7 and provided with a distributor ring 95 80 85 90 95 100. The conductors 86 extend to the solenoids 38 and return conductors 90 are connected to the distributing ring 89 which is placed in approximately the same horizontal plane as the solenoids 38 of the electrically operated shut off devices for the auxiliary reservoir.

The distributor ring 89 is connected by a conductor 91 to the distributing ring 83, and in this manner electric connections are established so that the platform and carrier switches may control the operation of the main shut off devices of the auxiliary reservoir. 105

Each of the scale platforms 55 has its 110 outer edge provided with a depending and outwardly extending shoe 92 and these shoes serve two purposes. First, the shoes are adapted to ride under and engage a vibratory rail 93 carried by blocks 94 loose 115 on guide posts 95 mounted in C shaped brackets 96 secured to the uprights 2 and 3 of the machine, as best shown in Fig. 2. The blocks 94 are supported on the guide posts 95 by coiled cushion springs 97 and said 120 guide posts may be conveniently in the form of bolts retained in engagement with the bracket 96 by nuts. On the vibratory rail 96 is mounted an electrically operated vibrator 97 and when this vibrator is placed 125 in operation, sufficient vibrations are imparted to the rail 93 and the shoes 92 to vibrate the scale platforms 55. Vibrations of the scale platforms 55 will cause material placed in the receptacles on the scale plat- 130

forms to evenly pack therein with no lost space and consequently receptacles can be completely filled if so desired.

The shoes 92 serve a further purpose of positively raising and lowering the scale platform 55, so that for any unseen reason a receptacle should fail to be filled the platforms will be actuated to control the electrical circuit of the machine. To this end, 10 the rear end of the vibratory rail 93 has an inclined or cam portion 98 which is encountered by the shoes 92 and the platforms 55 are lowered. As the shoes 92 travel off of the vibratory rail 93 the inclined or 15 a cam portion 99 of an auxiliary rail 100 is encountered, said rail being supported by a bracket 101 from the upright 4 of the machine. The lowering of the platforms 55 by the end of the vibratory rail 93 and the 20 elevating of said platforms by the end of the auxiliary rail 100 positively makes and breaks the electric circuit at the carrier knife switch 77, independent of the loading of the receptacles on the scale platforms. 25 Suitably supported in a horizontal plane with or slightly above that of the rotary carrier 54 is a loading and unloading platform 102 provided with endless conveyors 103 and 104, the former being employed for 30 conveying receptacles to the filling machine and the latter for removing the receptacle. These endless conveyors may be operated in timed relation to each other and to the rotation of the rotary carrier 54 by being driven 35 from the vertical drive shaft 7 of the machine. For this purpose, the shaft 7 has a horizontally disposed gear wheel 105 above the spider 6 and said gear wheel meshes with beveled gear wheels 106 on shafts 107 40 extending outwardly to impart movement to the endless conveyors 103 and 104, said shafts being supported in suitable bearing by the spider 6 and the platform 102.

On the platform 102 is a loading device in 45 the form of a vertical shaft 108 journaled in a bearing 109 of the platform 102. The lower end of the shaft 108 has a double crank 110 with one end thereof connected by a coiled retractile spring 111 to the platform 102. The opposite end of the double crank 110 has a pin and slot connection 112 with a bell crank 113 pivoted on the lower end of a depending bearing 114 of the platform 102. The bell crank 113 extends into 50 the path of trip members 115 carried by the rotary carrier 54, said trip members corresponding in number to the scale platforms 55 and positioned relative to said platforms so that the shaft 108 will be rocked when 55 each scale platform reaches a defined position relative to the loading device.

Each trip member 115 is longitudinally adjustable in a support 116 carried by a clutch member 117 and a set screw 118 or 60 similar fastening means is employed for fix-

ing the trip member relative to the support 116. The clutch member 117 normally engages the lower clutch end of a bearing 119 depending from the rotary carrier 54, and the clutch member 117 is held in an adjusted position by a cap 120 detachably mounted on the lower end of the bearing 119. It is therefore possible to set the trip member at a desired angle and in a lateral plane so that it will properly engage the 75 bell crank 113.

Mounted on the upper end of the rock shaft 108 are cranks 121 and adjustably connected to said cranks, as at 124, are parallel loading arms 122 connected by a pin 123. 80 These loading arms 122 are adapted to be swung inwardly towards the rotary carrier 54 to swing a can or receptacle on to a scale platform 55, and the outer ends of said loading arms have curved extensions 125 which prevent more than one can or receptacle being shifted by the loading arms 122. 85

Mounted on the platform 121 is a can or receptacle abutment 126 over and under which the parallel loading arms 122 swing to shift the can or receptacle along said abutment on to the scale platform, and the abutment 126 retains the cans or receptacles on the loading conveyor 103 until such time as a scale platform is in position to receive a can or receptacle. Connected to the abutment 126 is the resilient retaining member 127 adapted to engage the pin 123 of the loading arms 122 and temporarily hold the loading device at the limit of its outward movement, besides cushioning a return movement of the loading device due to the action of the retractile spring 111. 90

The platform 102 has guide rails 128 at the sides of the loading conveyor 103, and one of these guide rails is provided with an adjustable guide 129 which extends in the direction of the periphery of the rotary carrier 54 or towards the vibratory rail 93. 95 Connected to the adjustable guide 129 is a resilient finger 130 and when a can or receptacle encounters this finger the can or receptacle is shifted so as to engage the projection 72 of the platform switch and close the switch arm 70, thus establishing a circuit which energizes the solenoids 38 of the feed shut off devices and said solenoids open the devices against the action of the springs 42 so that material may flow through the discharge spouts 27 into the cans or receptacles on the scale platforms 55. 100

At the unloading conveyor 104 there are guide rails 131 and 132 extending above the rotary carrier 54 and these guide rails guide a loaded can or receptacle from the rotary carrier on to the unloading conveyor 104. 115

Mounted on the rotary carrier 54 is an annular abutment 133 in a plane above the inner ends of the scale platforms 55, said abutment limiting the inward movement of 120

the cans or receptacles on to the scale platforms.

Before considering the operation of the machine reference will be had to Figs. 4 and 5 showing a modified form of operating mechanism for the agitators 30 in the discharge nipples 26 and spouts 27 of the auxiliary reservoir. In this modification the agitator rail is in the form of a rack 134 normally engaged by a pawl 135 fixed on the outer end of each agitator shaft 32, and the retractile force of a spring 136 holds the pawl normally in engagement with the rack 134, so that as the auxiliary reservoir is revolved the pawl 135 will ride over the teeth of the rack 134 and impart a rocking movement to the agitator shaft 32.

In operation, and assuming that the drive shaft 7 is driven from a suitable source of energy, the rotary carrier 54 and the auxiliary reservoir are revolved in unison in clockwise direction. The material is maintained at a constant level within the auxiliary reservoir and is agitated within the reservoir nipples 26 so that the material will freely flow through the discharge spouts 27 when the same are open.

Further assuming that the loading conveyor 103 contains cans or similar receptacles, with one of the cans or receptacles against the abutment 126, the loading arms 122 will be eventually actuated by the trip member 115 of the rotary carrier 54, and a can or receptacle will be shifted onto the scale platform 55 adjacent the abutment 126. The can or receptacle will be pushed into the receiving member 63 and against the abutment 67 of the scale platform where the can will be held until it encounters the finger 130 when it is further shifted to close the platform switch and establish an electric circuit that energizes the solenoids 38 of the shut off device above the can or receptacle. As pointed out in the beginning the energizing of the solenoids 38 separates the shut off members 45 so that the spout 27 will open and permit of material flowing therethrough into the can or receptacle on to the scale platform 55. During the filling of the can or receptacle the platform 55 is vibrated and the filling continues during the rotary movement of the carrier 54 until the scale platform is overbalanced, which indicates that the can or receptacle has received a predetermined quantity of material. Overbalancing of the scale platform 55 opens the carrier switch 77 and the electric circuit to the solenoids 38 is broken so that said solenoids are de-energized, permitting of the spring 42 associated with said solenoids to actuate the shut off members 45 and close the discharge spout 27. The loaded can or receptacle eventually encounters the guide rails 131 and is shifted on to the unloading conveyor 104, and of course while this is tak-

ing place other cans or receptacles are being received by scale platforms and properly filled with material.

It may be found that the scale platform switches may be constructed so as to control the energizing of the solenoids 38, without the use of the carrier switches 77, but I prefer to use both switches so as to avoid excessive arcing at the scale platform switches and furthermore as a safeguard for fear that something should happen to a platform switch, in which case an emergency connection would be established so that the carrier switch would temporarily serve the purpose of controlling the operation of the feed shut off devices.

From the foregoing it will be observed that I have made certain improvements or refinements in connection with the machine disclosed by my prior patents, and it is these improvements which make the machine more practical from a commercial and manufacturing standpoint, particularly the former, as the machine is capable of handling any kind of material, liquid or granular, that is to be placed in receptacles.

What I claim is:—

1. A filling machine comprising a rotary receptacle carrier, scale platforms carried thereby adapted to receive receptacles to be filled with predetermined quantities of material, a reservoir movable with said carrier and adapted to supply material to the receptacles on the scale platforms, normally closed and electrically opened means controlling the supply of material from said reservoir to the receptacles, means on each scale platform adapted to open said means, and electrically operated means for vibrating said scale platforms during the filling of the receptacles thereon.

2. In a filling machine adapted to receive receptacles, filling means for the receptacles, electro-mechanical means controlling said filling means, movable platforms to receive the receptacles, means successively actuated by the placing and filling of receptacles on said platforms controlling the operation of said electro-mechanical means, and means to move said platforms with filled receptacles thereon so that the receptacles may be removed.

3. A filling machine as characterized in claim 2, wherein a rotary carrier supports said movable platforms and by its motion causing receptacles to be discharged from the platforms.

4. In a rotary filling machine, adapted to receive receptacles, mechanically closed and electrically opened filling means for the receptacles, platforms to receive the receptacles and adapted to be lowered and raised, means actuated by lateral movement of a receptacle on a platform to cause said filling means to open, means actuated by the

weight of a filled receptacle on said platform to cause the platform to lower and the filling means to close, and means adapted to raise the lowered platform with a filled receptacle thereon.

5. A filling machine as characterized in claim 4, wherein a loading device actuated by the rotary motion of the machine places receptacles on the platforms and the motion of the machine causes receptacles to be discharged therefrom.

6. In a rotary filling machine, individual movable scale platforms, a loading and unloading platform in the same plane as said scale platforms, a loading device on said loading and unloading platform operated in timed relation to the movement of said scale platforms, filling means for the receptacles set in operation by the placing of a receptacle on a platform by said loading device, means causing a cessation in the operation of said filling means by a depression of a scale platform due to the weight of a

filled receptacle thereon, and means for raising the platform with a filled receptacle thereon so that the filled receptacle may be shifted on to said unloading platform.

7. A rotary filling machine as characterized in claim 6, wherein an adjustable trip member associated with each scale platform operates said loading device.

8. In a rotary filling machine, scale platforms adapted to have receptacles placed thereon, filled and the platforms depressed by the weight of filled receptacles thereon, a vibrating rail, a raising rail, and means carried by each platform to successively engage said rails so that said platforms will be vibrated during the filling of the receptacles and raised after being filled.

In testimony whereof I affix my signature in the presence of two witnesses.

GEORGE W. BLAKE.
